UNITED STATES PATENT OFFICE.

THEODOR HOFRICHTER, OF TETSCHEN, AUSTRIA-HUNGARY.

UMBRELLA-COVER.

SPECIFICATION forming part of Letters Patent No. 628,006, dated July 4, 1899.

Application filed May 20, 1898. Serial No. 681,222. (No model.)

To all whom it may concern:

Be it known that I, THEODOR HOFRICHTER, manufacturer, a subject of the Emperor of Austria-Hungary, and a resident of Tetschen, Bohemia, Austria-Hungary, have invented 5 certain new and useful Improvements Relating to Umbrellas, of which the following is a specification.

The subject of the present invention is an 10 umbrella whose cover may be easily removed and replaced by another one. Among the advantages of such a construction are the fact that it can be readily transformed into a parasol, or vice versa, and that it can have 15 the cover changed to harmonize with the color of a lady's costume, thereby avoiding an expensive outlay for umbrellas and parasols.

In the accompanying drawings, Figure 1 shows the umbrella-frame. Fig. 2 is an 20 side view of the cover. Fig. 3 is a front view of one of the ribs of the frame. Fig. 4 is an edge view of the same. Fig. 5 is an outside view of the cover. Fig. 6 shows the separable fastening open. Fig. 7 shows the fastening closed.

The frame of the umbrella does not differ from those used hitherto except that the ribs are provided at or near their ends and at other suitable points with eyes *b b'*. The 30 cover *c* is provided on its inner side with buttons *f f'*, corresponding in position to the eyes in the ribs and preferably similar to those used on gloves, having compressible spring portions adapted to enter and engage with 35 the eyes. To the center of the cover is attached a sleeve *g*, having a slot *i*. The stick *h* of the umbrella has a spring-catch *k* in its upper end.

To cover the umbrella, the sleeve is slipped over the stick until the slot engages with the 40 spring-catch. The buttons *f f'* are then forced into the eyes *b b'* in the ribs *a*, and the umbrella is ready for use.

It will be seen that the operation can be quickly and readily performed and the cover 45 can be as quickly taken off.

By having the buttons secured upon the inner surface of the cover the outer surface is not marred nor its beauty impaired. It has no rows of eyelets showing nor any lacings or 50 other fastening devices, but retains the usual appearance of an umbrella-cover. This absence of anything on the outside to render the umbrella conspicuous is a decided advantage from a commercial point of view. 55

Having thus described my invention, what I claim, and desire to secure by Letters Patent, is—

In an umbrella, the combination with a stick having a catch in its upper end, of ribs 60 each having eyes formed therein, a cover, a sleeve permanently secured to the center of the cover and adapted to slip over the end of the stick and be removably held by the catch, and spring-fastenings permanently secured 65 to and projecting inwardly from the inside of the cover and adapted to engage separably with the eyes in the ribs, substantially as described.

Signed by me this 28th day of March, 1898. 70

THEODOR HOFRICHTER.
